LIQUID HEATER

Heinrich Vorkauf, Berlin, Germany, assignor to
 La Mont Corporation, New York, N. Y., a corporation of New York

Application May 17, 1934, Serial No. 726,061
 In Germany May 17, 1933

13 Claims. (Cl. 122—406)

This invention relates to feed preheater or economizer installations in connection with boilers or evaporators of the type in which the fluid to be evaporated is positively circulated. The invention is particularly concerned with the method and means of maintaining flow of the fluid through the preheater or economizer.

In the operation of boilers and evaporators frequently the feeding to the boiler or the evaporator of the fluid to be evaporated, that is the make-up feed, is subject to variations corresponding with variations in the load on the boiler or the evaporator, or such variations may be due to other causes. In boilers for generating steam from water, for example, the feeding of the make-up feed water to the boiler commonly is regulated by a valve or other flow control device which is actuated from a water level regulator which substantially determines the amount of water to be maintained in the boiler and which is brought into operation upon a variation of this amount of water. Feed control, however, may be made dependent upon other factors such as variations in the temperature or in the quantity of the steam delivered from the boiler. Such methods of feed control also have been utilized in connection with economizers or preheaters through which the water or the fluid to be evaporated is passed in order to heat the fluid before entering the boiler or the evaporator and to reduce the temperature of the heating gases or other heat vehicle so as to improve the efficiency of the plant.

In such preheater or economizer apparatus it is recognized that when the flow of the fluid to be heated is stopped by the control device actuated in accordance with the particular conditions in the evaporator or the boiler, the preheater or economizer is subjected to adverse conditions. For example, if the feed is shut off at a time when the heating surfaces of the economizer are subjected to relatively high heat, steam or vapor may be generated upon these surfaces or dissolved or entrained air may be liberated in the water or fluid. Unless provision is made for the circulation of the fluid in the economizer so that the steam or vapor or the air may be freed from the water, this vapor or air may become pocketed in the economizer and the heating surfaces, being not wetted by the water, may become overheated. The presence of air in the economizer or preheater, especially when the heating surfaces or the tubes thereof are made of wrought iron or steel, increases the opportunity for the formation of rust and the

corrosion of such tubes or heating surfaces. Moreover, the evaporation of the fluid or water which carries scale-forming materials, leaves the scale deposited upon these surfaces. When, however, a continuous flow of the fluid to be heated is maintained, the accumulation of steam or vapor or air is avoided, the heating surfaces are continually wetted and thereby prevented from overheating, corrosion is reduced or eliminated and the deposition of the scale-forming materials upon the surfaces is also prevented by the force of the flowing fluid.

The present invention has for its object the prevention of these deleterious conditions in preheaters or economizers which are used in connection with boilers or evaporators of the type in which a positive circulation of the water or of the fluid being heated and evaporated is maintained. This positive circulation of the water may be accomplished in a closed circuit in which a positively acting fluid circulating means, such as a pump, may be connected and in which circuit also heating surfaces or heating elements for the generation of the vapor or the steam are connected, to which and through which heating surfaces or elements the positively acting fluid circulating means causes to flow water or the fluid being heated. In such a boiler or evaporator utilizing positive circulation of the fluid being evaporated, according to the invention, a connection is so arranged between the circuit or conduit through which the positively acting circulating means forces the fluid and the conduit through which the make-up feed is delivered to the preheater or economizer and in such relation to the device controlling the feeding of the make-up feed to said boiler or evaporator that, when the make-up feed is shut off and, therefore, when the flow of the water or of the fluid to be evaporated through the economizer or preheater is stopped, water or fluid from said circuit may be delivered to the preheater or economizer for flow therethrough so as to maintain the temperature of the economizer at a sufficiently low degree to prevent damage and to prevent the corrosion and the deposition of scale-forming materials referred to above.

While heretofore it has been proposed to maintain circulation of the water through an economizer by means of a water circulating device such as a pump, in a circuit in which, as a separate circuit auxiliary to a steam generating or evaporator plant, the pump and the economizer elements are connected, according to the present invention a connection is made from the circu-

lating circuit of the generator or evaporator itself to such a point in the path of the flow of the fluid to the economizer as will cause water or the fluid being circulated to be delivered from 5 the positively acting circulating means of the steam generator or the evaporator through the economizer to maintain the flow of fluid therethrough. While said known installations have the advantage of maintaining the circulation of 10 the water within the economizer itself, an auxiliary circulating device is required and the separation of the steam or vapor from the water, if generated, must be provided. In the arrangement utilized in the present invention such auxiliary circulating means are not necessary as 15 the positively acting circulating device may be utilized to force the water or the fluid through the economizer, any steam or vapor formed being carried with the fluid into the steam and water 20 separating space of the steam generator or the evaporator itself.

Preheater installations for steam generators with forced circulation also heretofore have been known in which water is delivered through the 25 preheater by the circulating pump in order to prevent too low a temperature in the economizer. In such a preheater installation it is necessary, with a large amount of feed water flowing through the economizer, to deliver a large amount of 30 water from the circulating pump in order to prevent too low a temperature of the water in the economizer while, with a small flow of feed water or with the feed shut off, the temperature in the preheater tubes may become sufficiently high so 35 that no circulation from the circulating pump is caused to take place. This type of circulation through the economizer, therefore, does not bring about a continuous flow of water through the economizer and has, accordingly, the disadvantage inherent in the interrupted flow as described 40 above.

In a steam generator or evaporator having a closed circuit, by means of the positively acting circulating device the water or the fluid being 45 evaporated is circulated through steam or vapor generating elements, which elements are connected to a steam and water separating space, such as a drum, and the water separated may be returned to the water circulating device for re-circulation through the circuit. In such a case 50 or in such apparatus as include a steam and water separating space, the economizer may be arranged to discharge the heated feed water or the heated make-up fluid into such a space, any steam or vapor generated by evaporation in the 55 economizer being also discharged to and separated in said space from the water, the water or fluid heated in the economizer being mixed with the water or fluid of the circulation circuit for flow therethrough under the action of the 60 positively acting circulating means or pump.

In such a plant within the scope of the invention there may be provided, as stated above, from the discharge of the circulating means or pump 65 a connection to the pipe or conduit through which the feed is delivered to the economizer. Such a connection is made at a point between the water or fluid inlet end of the economizer and the controlling device, such as a valve, which controls 70 the feeding of the make-up water or fluid to the economizer. In said connection from the circulating means to the feed conduit or pipe also may be included a valve or other device for controlling the flow of fluid or water from said circulating means to said feed pipe. By suitably

arranging and connecting these valves or other fluid control devices in relation to each other and to the means actuating the feed control device subject to the variations in a selected condition within the steam generator or evaporator, such as the water level or the temperature, as referred to above, fluid may be delivered by the circulating device to the economizer when the feed control device is shut off or when the flow therethrough is reduced. On the other hand, 10 when the make-up feed water or fluid to be evaporated is again to be delivered to the steam generator or the evaporator and the feed control device or valve is accordingly open, the control device or valve in said connection from the circulating means or pump may be closed or throttled so as to stop or reduce to the desired degree 15 the flow of the water or of the circulating fluid from the circulation circuit of the steam generator or the evaporator.

It thus will be understood that, whereas the protection of the economizer or preheater is accomplished by the arrangement and method of the invention during the time when the feeding of the make-up feed water or fluid to be evaporated is stopped or so reduced as to cause the deleterious conditions to be present in the economizer, the invention also provides that when the feeding of the water or of the fluid again takes place, the circulation of the water from the generating circuit is stopped or is reduced to any desired degree. It thus will be clear that the function of the economizer or the preheater, as a fluid heating apparatus for improving the efficiency 30 by abstracting heat from gases or other heat vehicles which otherwise might be wasted, is maintained.

The invention will be more clearly understood from a description of the drawing in which:

Figure 1 shows a steam generating plant with an economizer and embodying the features of 40 the invention.

Figure 2 shows a section through the make-up feed valve.

Figure 3 shows a section through the valve controlling the flow of circulating water to the economizer.

Figure 4 shows a modification of the control apparatus utilized in the invention.

Figure 5 shows another modification of the control apparatus of the invention.

In Figure 1 is shown a boiler plant having a furnace space 1 enclosed by furnace walls 2. Fuel burners such as, for example, those which may burn powdered fuel or those which may burn oil, are shown at 3 in the rear wall 4 of the furnace.

In the space above the furnace constituting a passage for the gases from the furnace and enclosed by the upper portions of the walls 2 and 4 and by the front wall of the structure are mounted extensions 12 of tubes 10, which in the furnace, extend along the face of the walls 2. The extensions 12 of said tubes are arranged in serpentine form in each half of the space to form 65 bundles of tubes over which the gases from the furnace flow on their way toward the flue. Said tubes 10 and 12, therefore, constitute the steam generating tubes subjected to both radiant heat and convection heat and in the particular steam 70 generating plant illustrated, are formed as continuous tubes which, at their lower ends, are connected to headers 14 and 15. It will be noted that some of the tubes from the header 14 extend downwardly along the wall 2 and along the bot- 75

tom wall 5 of the furnace and upwardly along the opposite wall 2 to form part of the bundle of tubes on the opposite side of the gas space. Others of the tubes extend from the header 15 in like arrangement to form part of the bundle of tubes 12 on the opposite side of the structure from the header 15.

The discharge ends of the tubes in the installation shown in Figure 1 are connected at the bottom portion of a drum or steam and water separator 18 within which is mounted a baffle 20 between the walls of which the steam and water may be discharged upwardly against a deflector 21, the water being thrown to either side of the baffle 20 and the steam being liberated into the space 22 of the drum 18.

From the water space of the drum 18 a connection is made by the pipe 24 to the suction of the circulating pump 26 suitably mounted and driven by a motor or other power means 28. The discharge of the pump is connected by the pipe 30 and its extension 31 to the headers 15 and 14 to which, as described above, the water inlet ends of the tubes are connected. Said water inlet ends 25 may be provided with water restricting devices or orifices to limit the amount of water entering each tube in the manner and for the purposes of steam generation as described in the United States Letters Patent No. 1,884,979 granted

30 October 25, 1932.

The pump may draw the water from the water space of the drum 18 through the pipe 24 and deliver the water to the headers 14 and 15 from which the water is distributed into the different tubes 10 connected to these headers. The steam as it is generated flows through the tubes together with the water and is discharged into the drum 18, the excess water being separated in the drum 18 to be drawn again by the pump for delivery to the headers 14 and 15. The circulation of the water thus occurring through the steam generating tubes and through the circuit is produced, whether or not water is fed to the boiler by a feeding means, so long as sufficient water remains in the drum 18 to supply the suction of the pump 26.

In the space 33 above the bundles 12 of the tubes may be mounted a superheater or other heat exchanger if desired. Above this space 33 or in other suitable relation to the tubes 12 to receive the gases after flow thereof over the tube bundles 12 may be mounted economizer tubes 34. In the arrangement shown in Figure 1 said economizer tubes have one end thereof connected to the drum 18. Conveniently, as illustrated in the drawing, these ends of the tubes may be connected to the space between the baffles 20 so that any steam or vapor discharged from these economizer tubes may be separated from the water discharged therewith in the manner described above in connection with the steam generating tubes, the other ends being connected to headers 36 and 37.

To the headers 36 and 37 through a pipe 40 and its extension 41 the feed pump 42 or other feeding device may be connected. In the pipe 40 is inserted a feed controlling device or valve 50 which may be of any convenient type. In the particular embodiment shown in the drawing the valve 50 is connected to a water level regulating device 46 suitably mounted on and connected to the steam and water spaces of the drum 18 to be subjected to variations in the water level within said drum.

75 The water level regulator diagrammatically

illustrated in Figure 1 may be of the type in which a fluid pressure is produced by the steam or vapor contacting the element of the regulator, which steam or vapor is condensed when the water or fluid in the drum 18 rises and correspondingly the water rises within said element in contact therewith, the condensation reducing the pressure within the element. Conversely a fall in the water level increases the steam contact with the element and evaporates more fluid within the element thus raising the pressure. The increase or decrease of the pressure is transmitted through the pipe or lead 54 to the diaphragm 52 shown in Figure 2.

The water level regulator 46 operates in the usual manner under variation of the water level with load on the steam generator and many different devices may be used for this purpose. In the particular device illustrated, as will be clear from Figure 2, the fluid pressure which is brought to bear on the diaphragm 52 through the lead 54 connected to the water level regulator 46 causes the diaphragm to bear upon a flange 56 at the upper end of the stem 58 of the valve 50 and acts against the pressure of the spring 60 tending to close the valve. The stem 58 passes through a stuffing box 62 and carries at its lower extremity the valve discs 64 of a balanced valve, the discs 64 bearing, when closed, upon seats 65 and 66 of the valve structure in the usual manner.

Thus it will be clear that when the water level rises in the drum 18 condensation will take place in the element of the water level regulator 46 and the pressure in the lead 54 and, therefore, the pressure upon the diaphragm 52 will be reduced. The spring 60, acting against this pressure, therefore, may act to throttle or close the valve 50 so that its discs 64 approach or become seated upon the seats 65 and 66. Conversely, when the water level in the drum 18 falls the fluid pressure within the element of the water level regulator 46 is raised and pressure is brought upon the diaphragm 52. When this pressure becomes sufficient to overcome the spring 60 the valve discs 64 are moved away from their seats and the valve is opened permitting fluid or water from the feed pump 42 to be delivered through the pipe 40 and its extension 41 to the headers 36 and 37 of the economizer. From these headers the water then is forced through the tubes 34 of the economizer and delivered to the drum.

Also connected to the lead 54 is the control valve 70 in the pipe 71 connected between the discharge pipe 30 from the circulating pump and the pipe 40, being connected to said pipe 40 at a point thereon between the headers 36 and 37 and the valve 50. As will be clear from Figure 3, the construction of the valve 70 may be substantially the same as that of the valve 50 with the exception that the valve discs and their seats are in reverse relation to the steam and its motion to that of Figure 2. Thus, when pressure is brought to bear upon the diaphragm 72 of the valve 70 acting through the flange 76 and the stem 78 against the spring 80, the valve discs 84 are moved against their seats 85 and 86. Conversely, when pressure is relieved from the diaphragm 72 the valve discs 84 will be lifted from their seats 85 and 86 by the action of the spring 80, thus permitting water to flow from the discharge pipe 30 through the pipe 71 to the feed pipe 40 and to be delivered under the pressure of the circulating pump 26 to the headers 36 and 37 and through the tubes 34 of the economizer.

Flow of the water delivered by the pump 26

through the pipe 71 reversely through the pipe 40 is prevented because, as now will be apparent when the valve 70 is opened the valve 50 is closed or throttled to prevent substantial flow therethrough. It will, therefore, be understood that when the flow of the feed water through the economizer is stopped or reduced by the closing of the valve 50 under the action of the water level regulator 46, circulation of water through the 10 economizer is maintained by the opening of the valve 70, permitting flow of the circulating water to and through the economizer under the action of the circulating pump.

Instead of the water level regulator of the type 15 utilizing an element within which a fluid pressure is generated, as illustrated in Figures 2 and 3, mechanical water level regulating apparatus having a float mechanically operating a valve may be used, as shown in Figure 4. As shown in 20 the figure, a float 90 mounted at the end of a lever 91 may be positioned within the drum 18. The lever 91 may be pivoted upon a shaft 92 extending through the wall of a box 93 mounted upon the drum 18. At the outside of the wall of 25 the box 93 is the lever 94. Connected to the lever 94 is a link 95 having its other extremity connected to the stem of the valve 50. Also connected to the lever 94 is the upwardly extending link 96 having its other extremity connected 30 through a reversing lever 97 pivoted at 98. To the opposite extremity 99 of the reversing lever by means of link 100 connection is made to the stem of the valve 70. The valve 50, as in the embodiment previously described, is located in 35 the feed line to the economizer, the valve 70 being located in the connection between the discharge pipe of the circulating pump and the feed line, as above described. In the arrangement shown in Figure 4, the valves 50 and 70 may be 40 alike.

It will be apparent that as the water level rises in the drum 18 the lever 94, acting through the link 95 will press downward the stem of the valve 50. The valve 50, therefore, should be so 45 constructed as to close under this motion of the mechanism. When the float thus moves the lever 94, through the link 96, the lever 97 and the link 100, the stem of the valve 70 will be raised. As in the particular arrangement being 50 described the valve 70 is like the valve 50, the valve 70 will be opened upon this motion of the mechanism. It will be clear, therefore, that when the water level rises to the point where it is necessary to shut off the feed by closing the 55 valve 50, at the same time the valve 70 will be opened and flow of the water through the pipe 71 may take place to the economizer as described above.

While in the illustrated embodiments of the 60 control devices the valves controlling the flow of the feed and of the circulating water which is by-passed from the discharge of the circulating pump to the economizer are actuated by a single water level regulator, each of said valves 65 may be controlled by separate water level regulators or may be actuated separately or together by other devices which, for their action, depend upon the amount of the steam or vapor produced or upon other factors related to the steam 70 generation. In each case, however, when the flow of the feed water through the economizer is stopped or is so reduced as to cause the deleterious conditions above referred to to rise, the water or circulating fluid is by-passed through 75 the economizer under the action of the circulat-

ing pump to maintain sufficient flow in the economizer to prevent such conditions. And conversely, when the normal flow of the feed water through the economizer or sufficient flow to prevent said undesirable conditions occurring 5 is established, then the delivery of the circulating water to and through the economizer may be stopped or so reduced as to secure the desired economizing effect obtainable with the flow of feed water through the economizer. In some 10 cases it may be desirable to maintain a flow of the circulating water through the economizer in addition to the flow of the feed water in order that a sufficiently high velocity of flow in the tubes or over the surfaces of the economizer 15 may be maintained.

Instead of the control valve 70 in the pipe 71 a back pressure or check valve 120 may be utilized, as shown in Figure 5, which permits flow only in the direction from the discharge 20 pipe 30 of the circulating pump toward the feed pipe 40. When a normal amount of feed water is being delivered to the economizer the resistance in the economizer corresponding with such an amount of flow may be sufficient to require a 25 pressure of the feed water in the feed pipe 40 which is higher than that in the discharge pipe 30 of the circulating pump. It thus will be seen that a back pressure valve or a check valve 120 arranged at 70 as just described, will prevent 30 flow of the feed water through the pipe 71 toward the circulation circuit and also flow of the circulating water toward the feed pipe 40 will be prevented by the excess pressure of the feed water. Such a valve 120, however, may open 35 when the pressure in the feed pipe 40 falls to a point below that of the pressure on the other side of the back pressure valve 120 caused by the circulating pump. Flow then may take place 40 from the circulation circuit under the action of the circulating pump through the check valve 120 to the economizer. In this embodiment a check valve 122 may replace valve 50 in pipe 40 to prevent flow of the circulating water in the feed pipe 40 toward the pump 42 or the supply 45 when the pressure of this feed supply falls.

In order more easily to control the conditions of pressure in the feed pipe 40 or in the by-pass pipe 71 which may be utilized for the purposes just described, orifice plates may be installed at 50 110 in the feed pipe 40 and at 112 in the by-pass connection 71. The orifice 110 adds to the resistance of the economizer itself which must be overcome by the feed water pressure and thus the pressure of the feed water may be maintained 55 sufficiently high under normal feeding to be greater than the pressure in the discharge pipe 30 of the circulating pump. The orifice provided by the plate 112, however, may be utilized to limit the amount of water which is delivered by 60 the circulating pump to the economizer.

The arrangement shown and described above in which the economizer tubes discharge into the space between the baffles 20, into which space also the steam generating tubes discharge the 65 mixture of steam and water, has the advantage that in the normal operation of the economizer and steam generating plant the feed water may become fully heated to the steam generating temperature. Moreover, when any steam is generated in the economizer either during the normal feeding of the feed water or when the feed water is shut off and the circulating water is passing through the economizer, the steam and water mixture thereby produced, if any, will have 70 75

the same opportunity for separation as that which is discharged from the steam generating tubes themselves.

The invention is not limited to the particular arrangement of apparatus and the particular types of steam generating and economizer constructions illustrated but includes all steam generating and evaporating plants in which circulating water is by-passed from a circuit through which the water is forced for circulation in the steam generator or evaporator to flow through the economizer so as to maintain a flow through the economizer for the purposes described.

Having thus described my invention I claim:

1. Steam generating plant comprising a steam generating circuit in which the water being evaporated is circulated by a positively acting circulating means, a feed water preheater connected to discharge into said circuit the feed water after being heated in said preheater, means for delivering circulating water from said circuit to said preheater and causing it to flow therethrough, and means for controlling the flow of said circulating water so delivered, said controlling means being constantly and directly actuated in accordance with variations in the rate of flow of feed water flowing through the preheater so that flow of water through the preheater in amount sufficient to protect said preheater is maintained with varying amounts of feed water delivered to the preheater.

2. Steam generating plant comprising a steam generating circuit in which the water being evaporated is circulated by a positively acting circulating means, a feed water preheater connected to discharge into said circuit the feed water after being heated in said preheater, a connection between the discharge of said circulating means and the water inlet side of the preheater, a flow controlling device in said connection, means for conducting feed water to said preheater, a device controlling the flow of feed in said conducting means, and means connected to said devices for actuating said flow controlling device in said connection in a predetermined relation to the operation of said device controlling the flow of feed to said preheater.

3. Steam generating plant comprising a steam generating circuit in which the water being evaporated is circulated by a positively acting circulating means, a feed water preheater connected to discharge into said circuit the feed water after being heated in said preheater, a connection between the discharge of said circulating means and the water inlet side of the preheater, a flow controlling device in said connection, means for conducting feed water to said preheater, a device controlling the flow of feed in said conducting means, and means for actuating said flow controlling device in said connection, said actuated means being connected to and being arranged in such relation to the operation of said device controlling the flow of feed water to said preheater that flow of circulating water is caused through said connection to said preheater in inverse relation to the flow of feed water to said preheater.

4. Steam generating plant comprising a steam generating circuit in which the water being evaporated is circulated under a pressure produced by a positively acting water circulating means, a feed water preheater connected to discharge into said circuit the feed water after passing through said preheater, means for delivering to said feed water heater the feed water under

pressure sufficient to produce flow through the preheater, and means constantly responsive to variations in said pressure for causing circulating water to flow from said circuit through said preheater when the pressure of said feed water is reduced to a predetermined amount in relation to the pressure of said circulating water.

5. Steam generating plant according to claim 4 in which flow restricting means are provided for modifying the flow producing pressure relation.

6. Steam generating plant comprising a steam generating circuit in which the water being evaporated is circulated by a positively acting circulating means, a feed water preheater connected to discharge into said circuit the feed water after being heated in said preheater, a connection between the discharge of said circulating means and the water inlet side of the preheater, a valve in said connection, a conduit carrying feed water to said preheater, a valve in said conduit, and means connected to said valves for opening said valve in said connection upon closing operation of said valve in said feed carrying conduit.

7. Steam generating plant according to claim 6 in which the operation of the feed valve is dependent upon a predetermined condition in the steam generator related to the requirement of water to be fed into the generator.

8. Steam generating plant comprising a steam generating circuit in which the water being evaporated is positively circulated, a feed water preheater connected to discharge into said circuit the feed water after passing through said preheater, means for causing water from said circuit to flow through said preheater, and means actuated in accordance with variations in the volume of water within said steam generating circuit and arranged to vary, constantly in direct relation to variations in said volume, the flow of water from said circuit through said preheater.

9. A heat exchanger plant comprising a heat exchanger of the type in which a fluid is positively circulated in a circuit, a fluid heater of the type in which the fluid being heated flows therethrough, said fluid heater being connected to discharge to said circuit the fluid heated therein, and means constantly and directly responsive to variations in the flow of fluid to said heater for causing circulating fluid from said circuit to flow through said fluid heater to maintain flow of fluid through said fluid heater upon variations of the delivery of the fluid to be heated therein.

10. Steam generating plant comprising a steam generating circuit in which the water being evaporated is positively circulated, a feed water preheater connected to discharge into said circuit the feed water after passing through said preheater, and means constantly and directly actuated in accordance with variations in the flow of the feed water for causing water from said circuit to flow through said preheater when flow of the feed water through said preheater is reduced to a predetermined point.

11. In a steam generating plant comprising a steam generating circuit in which the water being evaporated is circulated by a positively acting circulating means, a feed water preheater connected to discharge into said circuit the feed water after being heated in said preheater, a connection for by-passing water from the discharge side of said circulating means to the inlet side of said preheater and a check valve

in said by-pass opening toward said inlet side of said preheater, whereby water from the circulating means is by-passed to the preheater only when the feed water back pressure on said valve is less than the pressure caused by said circulating means.

12. In a steam generating plant comprising a steam generating circuit in which the water being evaporated is circulated by a positively acting circulating means, a feed water preheater connected to discharge into said circuit the feed water after being heated in said preheater, a connection for by-passing water from the discharge side of said circulating means to the inlet side of said preheater, a check valve in said by-pass opening toward said inlet side of said preheater, whereby water from the circulating means is by-passed to the preheater only when the feed water back pressure on said valve is less than the pressure caused by said circulating means, and throttling means in said connec-

tion for creating the desired pressure relations at said check valve.

13. In a steam generating plant comprising a steam generating circuit in which the water being evaporated is circulated by a positively acting circulating means, a feed water preheater connected to discharge into said circuit the feed water after being heated in said preheater, a connection for by-passing water from the discharge side of said circulating means to the inlet side of said preheater and a check valve in said by-pass opening toward said inlet side of said preheater whereby water from the circulating means is by-passed to the preheater only when the feed water back pressure on said valve is less than the pressure caused by said circulating means, and throttling means between said check valve and said inlet to said preheater for creating the desired pressure relations at said check valve. 20

HEINRICH VORKAUF.
